DESIGN FOR AN ORNAMENTAL CARD.

Design No. 13,023, dated July 4, 1882.

UNITED STATES PATENT OFFICE.

EDWARD H. RATH, OF NEW YORK, N. Y.

DESIGN FOR AN ORNAMENTAL CARD.

SPECIFICATION forming part of Design No. 13,023, dated July 4, 1882.

Application filed May 16, 1882. Term of patent 3½ years.

To all whom it may concern:

Be it known that I, EDWARD H. RATH, of the city, county, and State of New York, have invented a new and useful Design for Cards for Mantel, Bracket, and Easel Ornamentation; and I do hereby declare that the following, taken in connection with the photographs which accompany and form part of this specification, is a description of my invention sufficient to enable those skilled in the art to practice it.

Figures 1 and 2 illustrate my newly-designed card.

The leading feature of my design consists in a card upon which is printed, pasted, or otherwise fastened a plain or ornamented horseshoe, with or without a motto or print in the center of the same, and a sheaf of various natural or artificially-colored grasses placed to the right or left of the said horseshoe.

A is the card; B, the horseshoe; C, the sheaf of grasses; D, the binder, and E the motto or print. The horseshoe, sheaf of grasses, binder, and printing may be plain, ornamental, or colored, and are fastened to the card by any suitable means.

I claim—

1. The design for a card herein shown and described, the same consisting of the card A and the sheaf of grasses C.
2. The design for ornamental card herein described and shown, consisting of the card A, the horseshoe B, and sheaf of grasses C.
3. The design for card herein described and shown, consisting of the card A, ornamented horseshoe B, sheaf of various natural and colored grasses C, and binder D.
4. The design herein shown and described, consisting of the card A, horseshoe B, sheaf of grasses C, binder D, and motto or print E.

EDWARD H. RATH.
